UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

DRAFT RIGGING.

Application filed October 23, 1919. Serial No. 332,656.

To all whom it may concern:

Be it known that I, WILLIAM KELSO, a citizen of the United States, residing at Pittsburgh, in the county of Allegheny and 5 State of Pennsylvania, have invented certain new and useful Improvements in Draft Rigging; and I do hereby declare the following to be a full, clear, and exact description of the invention, such as will enable 10 others skilled in the art to which it appertains to make and use the same.

My invention relates to the construction of draft rigging for railway cars and is particularly directed to the production of simple, strong and durable means for pivotally connecting the car coupler to the draft yoke of the mechanism. Generally stated, this object is accomplished by providing the rear end or butt of the coupler with oppositely 15 extending liner blocks having front and rear concentric segmental cylindrical faces conforming to correspondingly curved faces on the interior of the draft yoke at its forward end, the draft yoke having a lateral opening 20 which is of less width than the diametric distance between the curved faces of the liner blocks but which is sufficiently wide to permit the passage of the liner blocks after 25 the coupler and yoke have been brought to 30 an angular position with respect to each other in the act of assembling or disconnecting the parts.

In the drawings illustrating the preferred form in which I contemplate applying the 35 principle of my invention, the scope whereof is pointed out in the claims,

Figure 1 is a side elevation of a draft yoke and car coupler constructed in accordance with my invention, the coupler head and a 40 portion of the coupler shank being omitted.

Figure 2 is a detail sectional view on the line 2—2, Figure 1.

Figure 3 is a detail sectional view on the line 3—3, Figure 1.

45 Figure 4 is a detail view showing the forward end of the draft yoke in vertical central section and the rear end of the coupler in side elevation.

Figure 5 is a front elevation of the draft 50 yoke.

In the drawings, 1 indicates the car coupler and 2 is the draft yoke of the draft rigging. As the head of the car coupler forms no part of this invention its details of construction are immaterial and may be of any 55

well known or desired character. The draft yoke 2, except for certain features of construction hereinafter covered by the claims, may be of any form desired, but as shown in the drawings it is preferred that the longitudinally extending yoke arms 3 between which the usual springs and followers or other cushioning unit (not shown) are located shall be arranged in vertical rather than in horizontal alinement, and that said arms and the portion of the yoke which interlockingly engages the butt of the coupler 1 shall be integrally united.

The rear end or butt of the coupler 1 is provided with oppositely disposed liner blocks 4 constituting pivot lugs or trunnions for pivotally and interlockingly connecting the coupler to the yoke 2. The front and rear faces of the liner blocks are concentrically curved and of convex segmental form, while their lateral faces 5 are preferably flat and parallel, so that the length of said liner blocks longitudinally of the coupler exceeds their transverse width. The curved rear faces 6 of the liner blocks together with the intervening curved rear end 7 of the coupler shank preferably constitute a continuous cylindrical bearing surface for transmitting buffing shocks from the coupler 1 to the draft yoke 2. The curved forward face of each liner block 4 is preferably stepped or shouldered at its outer end to form segmental lugs 8 which project forwardly beyond the curved surfaces 9 that are adjacent the shank of the coupler. 90

The forward end of the draft yoke 2 and the rear end or butt of the coupler are interlockingly connected. To effect this in an efficient manner the draft yoke is provided at its forward end with lugs 10 which project inwardly toward the shank of the coupler and between which the coupler shank extends. The rear or interior surfaces of these lugs are cylindrically curved to correspond to the forward faces of the liner blocks 4, being stepped or shouldered to provide rearwardly extending lugs 11 which are in alinement with the curved faces 9 of the liner blocks and which overlap the corresponding segmental lugs 8 on the latter, and 100 being formed with curved surfaces 12 mating with the forward faces of the corresponding lugs 8 of the liner blocks.

Spreading or separation of the forward ends of the arms 3 of the yoke, which is re- 110

sisted by the overlapping segmental lugs 8 and 11, is also resisted by a transversely extending tie or web 13 which separates the coupler butt receiving pocket of the yoke 2 from the opening between the yoke arms for the reception of the cushioning unit (not shown) of the draft rigging; and as a means for still further overcoming the spreading of the yoke arms 3 the latter are preferably 10 integrally connected at their forward ends by a tie or wall 14 extending forwardly from the tie 13 and closing one side of the coupler receiving recess of the yoke and integrally uniting the pulling lugs 10 of the yoke 2. The forward face 15 of the transverse tie member 13 is concavely curved cylindrically to correspond to the convex curvature of the rear end of the coupler butt, an extended bearing surface for receiving buff- 20 ing shocks in any angular position which the coupler and yoke may assume in service being thus afforded. The side wall 14 preferably diverges forwardly from the longitudinal axis of the yoke so as not to interfere with extended lateral swinging or pivotal movement of the coupler.

To enable the coupler and yoke to be brought into assembled relation the yoke is provided in advance of the tie member 13 30 thereof with a side opening 16 communicating with the recess or pocket of the yoke in which the butt of the coupler 1 is located when the parts are in assembled relation. The opening 16, which extends forwardly 35 between the pulling lugs 10 so as to receive and allow for lateral swinging of the shank of the coupler 1, is of sufficient height to permit the passage of the liner blocks 4 of the coupler, but its width is such that the liner blocks may not pass therethrough until 40 the coupler and yoke are at right angles to each other. When so positioned the liner blocks 4, which are of less width than length, may be entered through the opening 16, after 45 which the coupler 1 may be rotated to normal operating position. In disassembling the parts the above described operation is reversed, that is to say, the coupler and yoke are turned until they are at right angles to each other and then are disconnected. It will be observed that the liner blocks 4 50 are so proportioned as to prevent any chance of their escape from the yoke when in service position.

55 I claim:

1. In a draft rigging, the combination of a coupler and a draft yoke detachably and pivotally connected thereto, said coupler having oppositely disposed liner blocks provided with concentric convexly curved front and rear faces, and said yoke having arms

adapted to receive a cushioning unit between them and having at its forward end pulling lugs provided with curved faces adapted to engage said curved front faces of said liner blocks and having a transversely extending tie spaced rearwardly from said pulling lugs and connecting said arms and adapted to engage said curved rear faces of said liner blocks and having a wall extending forwardly from said transversely extending tie and rigidly connected to said arms and said pulling lugs.

2. In a draft rigging, the combination of a coupler and a yoke pivotally united thereto, said yoke having pulling lugs the posterior faces of which are stepped and concavely curved, an integral transverse tie-bar having its forward face concavely curved, and an integral side-wall which integrally connects said pulling lugs and tie-bar, said coupler having oppositely disposed liner-blocks of greater longitudinal length than transverse width, the pulling faces of said liner-blocks being formed with undercut stepped convexly curved surfaces corresponding to the pulling lugs of the yoke.

3. In a draft rigging, the combination of a coupler and a yoke pivotally united thereto, the yoke having its arms connected by an integral transverse tie-bar and having in advance of said tie-bar an integral tie-wall closing one side of the yoke, and having at its front pulling lugs the rear faces of which are rabbeted and concavely curved, and the coupler having oppositely disposed segmental liner-blocks of greater longitudinal length than transverse width, the forward faces of said liner-blocks being undercut and convexly curved to conform to the rear faces of the pulling lugs of the yoke.

4. In a draft rigging, the combination of a coupler and a yoke pivotally united thereto, said yoke having its arms connected by an integral transverse tie-bar having a concavely curved anterior face, and having in advance of said tie-bar an integral tie-wall closing one side of the yoke, said yoke at its front end having pulling lugs the rear faces of which are rabbeted and concavely curved concentric with said curved face of the transverse tie-bar, and the coupler having oppositely disposed segmental liner-blocks of greater longitudinal length than transverse width, the forward faces of said liner-blocks being undercut and convexly curved to conform to the rear faces of the pulling lugs of the yoke.

In testimony whereof I affix my signature.

WILLIAM KELSO.
